ELECTRONIC CONTROL FOR FILAMENT WRAPPING MACHINES

Albert M. Dexter, Jr., Farmington, Conn., assignor to Niles-Bement-Pond Company, West Hartford, Conn., a corporation of New Jersey

Application February 20, 1948, Serial No. 9,887

3 Claims. (Cl. 153—67)

1

This invention relates to winding machines and more particularly to a winding machine for tungsten wire in which a fine filament of tungsten is continuously wrapped about a core of wire of small diameter such as of steel while the wire forming the core is advanced at a uniform rate and maintained under tension.

An object of the invention is to promptly indicate breakage of the filament as it is being wrapped so that the machine may be promptly and automatically stopped as soon as a breakage occurs.

A feature of importance of the invention is that the breakage indicator forming the present invention requires no mechanical connection to the winding mechanism but depends upon light flashes reflected from a mirror rotated with the wrapping mechanism falling periodically on a photoelectric tube. By means of an electronic circuit within which the photoelectric tube is included, constant light flashes, or no light, falling on the photoelectric tube as the wrapping mechanism rotates maintain a stop motion device relay energized to open the main circuit contacts for the machine and stop its operation. Variable flashes occurring periodically during normal operation serve to deenergize the relay coil and maintain the main circuit contacts for the machine closed.

In forming tungsten filaments for high and low wattage light bulbs, it is the usual custom to wrap the filament around a mandrel or core of steel wire, the steel wire being continuously advanced under tension during the wrapping operation so that successive convolutions of the filament along the core will be equally spaced. After wrapping the filament the steel core is dissolved in an acid bath which effectively removes the steel and leaves the helically wound filament ready for cutting into proper lengths for assembly within the bulb.

As the filament is extremely fine, it is very difficult for the operator to determine when a break occurs in the filament during the winding or wrapping operation. Continued operation of the machine after breakage of the filament is wasteful. It is therefore a desirable feature of the invention to stop operation promptly when the filament breaks, and without the addition of mechanism increasing the tension on the filament.

To effect this stoppage advantage is taken of the difference in speed of the guide member for the filament and the filament carrying spool rotated with the guide member. The rotation of the spool is at a different and slightly increased

2

speed from that of the guide member by reason of the unwinding of the filament from the spool. After a break occurs in the filament the spool will rotate with the guide carrying member and at the same speed.

During normal operation of the wrapping mechanism due to the difference in speed of rotation of the guide member and spool, a mirror rotating with the guide member is periodically exposed to a light source through an opening in a member rotating with the spool. Reflected flashes from the mirror fall on a photoelectric tube and render this tube momentarily conducting to pass current through an electronic circuit. 10 These flashes will vary in intensity due to the mirror slowly passing the opening, the flashes first increasing and then decreasing. After a break in the filament the spool and guide member will rotate at the same speed so that there will be equally timed flashes of equal intensity with each revolution of the guide member or if the mirror is concealed there will be no flashes whatever. This is due to the relative positions of the mirror and opening remaining unchanged. 15 If the break occurs when the opening is above the mirror there will be a continuous series of flashes of equal intensity and at equal intervals, one with each rotation of the guide member and spool. If the break occurs when the mirror is concealed by the flange, there will be no light flashes at all. 20 This will be obvious by an inspection of Fig. 2 of the drawing. By the electronic circuit including the photoelectric tube the relay operating the stop motion is not affected by the periodic varying series of flashes of different intensity but is caused to be operated and open the main circuit for the machine by equal flashes equally timed or by no flashes at all falling on the tube.

It is therefore a primary object of the invention to provide an electronic circuit responsive to flashes of different types falling on a photoelectric tube included within the circuit.

In the accompanying drawing annexed hereto and forming a part of this specification, I have shown the invention embodied in a simple form of filament wrapping device but it will be understood that the invention can be otherwise embodied and that the drawing is not to be construed as defining or limiting the scope of the invention, the claims appended to this specification being relied upon for that purpose.

In the drawing:

Figure 1 is a side elevation in section showing the principal parts of a simple filament wrapping machine.

Fig. 2 is a front elevation in section taken on the line 2—2 of Fig. 1, and

Fig. 3 is a diagram showing a preferred circuit for controlling a motor operating relay for the machine.

In the above mentioned drawing there has been shown but one embodiment of the invention which is now deemed preferable, but it is to be understood that changes and modifications may be made within the scope of the appended claims without departing from the spirit of the invention.

In Fig. 1 are shown the operative parts only of a winding machine which may have the stop motion relay controlling circuit forming the present invention. The rotating member includes a hollow shaft 10 and arm 12. The base for supporting this member and its rotating means are not shown, the rotating member being shown extending from a fixed member 14 which may be attached to a suitable base. The shaft 10 supports a spool 16 freely rotatable on the shaft on which is wound the filament 18. The arm 12 supports guides 20 in the form of rolls over which the filament 18 passes from its spool 16 to the wire 22 around which it is being wrapped.

The shaft 10 supporting the arm 12 is hollow and the steel wire for the core 22 is advanced by means (not shown) axially through the shaft, and after being wrapped by the filament 18 is wound upon a suitable drum 24 which may be rotated at a uniform speed by any appropriate means. The spool 16 is freely rotatable on its supporting shaft 10 so that it may rotate relatively to as well as with the shaft while the shaft and arm 12 are rotated to permit the filament 18 to unwind while the spool is rotated with the guiding member 12.

As shown in Fig. 1 the arm forming the guiding member 12 is keyed directly to the shaft 10 and has mounted thereon a disc 26 on the periphery of which is mounted a small mirror 28. The spool 16 on one of its faces is provided with a flanged member 30 fixed to the spool for rotation therewith, there being an opening 32 in the flange 30 aligned with the mirror 28.

From the above description it will be seen that during rotation of the shaft 10 and spool 16 at different speeds the mirror 28 will be directly below the opening 32 in the flange 30 after a number of revolutions of the shaft 10. Just before and after the mirror 28 is directly below the opening 32 for several revolutions, the mirror 28 will be partially below the opening. These phases increase as the mirror 28 slowly moves toward the position directly below the opening and then decrease as the mirror moves away from the opening. In the event of a breakage of the filament the spool 16 and shaft 10 will rotate together at the same speed and the relative positions of the mirror 28 and opening 32 will not change. The mirror 28 may be visible below the opening 32, partially visible, or completely out of sight by being hidden by the flange 30.

Adjacent the spool 16 and shaft 10 is a source of light 34 such as a small light bulb. A lens 36 is preferably mounted between the bulb and mirror 28 so that the light rays may converge upon the flange 30. When the mirror 28 is visible below the opening 32 in the flange, light from the bulb 34 will be reflected to a photoelectric tube 38 positioned adjacent the light source 34. The reflected flashes of light fall-

ing on the photoelectric tube 38 will increase as the mirror 28 slowly comes into a position below the opening 32 and will then decrease as the mirror passes the opening. The passage of the arm 12 at each revolution does not produce any interruption of these light flashes for the reason that the mirror 28 is angularly disposed relative to the position of the arm 12.

To actuate a stop motion or motor controlling relay 40 by means of the flashes of reflected light from the mirror 28 to the photoelectric tube 38 the following circuits have been devised, the diagram for the circuit being indicated in Fig. 3 of the drawing.

These circuits control energizing of relay 40 opening and closing the contacts of a motor circuit for operating the machine. With the relay 40 energized the motor circuit contacts are opened and the machine is thus stopped. So long as the coil of relay 40 is not energized the motor circuit contacts are closed to continue the normal operation of the machine. The function of the circuits shown in Fig. 3 is to energize the coil of relay 40 as soon as a break in the filament 18 occurs, and to maintain the coil of relay 40 deenergized during normal operation of the machine.

T_1 is a power transformer connected as an auto-transformer with primary and secondary connected series windings. The first section of tube V_1 is a diode rectifier. Following the current from one side of the line indicated at A. C., it flows to the plate of diode of D_1 (which forms a part of tube V_1) through diode D_1 , to the cathode of D_1 , through resistances R_3 , R_2 , R_1 , and potentiometer P_1 , and back to the end of transformer secondary 42. Due to the half wave rectification action of tube D_1 , no current flows through this tube on alternate half cycles. A pulsating uni-directional current therefore flows through tube D_1 , and due to the filtering action of condensers C_1 , C_2 and resistance R_3 , a steady D. C. voltage appears across the network consisting of resistances R_2 , R_1 , and potentiometer P_1 , the polarity of which is indicated in Fig. 3. This voltage may be called the B voltage supply.

T_2 is an audio coupling transformer with one end of its primary connected to the terminal of the B voltage supply and the other end connected to the plate of the second, or triode, section of tube V_1 . The cathode of the triode section of tube V_1 is connected to the slider of potentiometer P_1 in the B voltage supply network. Condenser C_3 forms a by-pass from the cathode of the triode portion of tube V_1 to the minus end of B voltage supply network to prevent degeneration in the cathode circuit as is the practice in amplifying stages. The grid of the triode section of tube V_1 is connected through resistance R_4 to the minus end of the B voltage supply. It will be seen, therefore, that the triode section of tube V_1 is biased to the extent of the voltage from the slider on potentiometer P_1 to B minus, and this slider should be adjusted until the triode section of tube V_1 is just drawing current, that is, not quite to cut-off.

Photoelectric tube 38 referred to above is connected between grid of triode in tube V_1 and a positive tap on the network formed by resistances R_2 , R_1 , and potentiometer P_1 . When this photoelectric tube 38 is illuminated, it becomes more conducting, and the current in flowing from the tap on the B voltage network through photoelectric tube 38, through resistance R_4 to the

minus end of B voltage network, makes the grid less negative; in other words, the triode D_1 is no longer biased negatively. Current flows from the plate of the triode section of tube V_1 to the cathode, therefore, whenever the photoelectric tube 38 is illuminated.

At this point it is well to consider the function of the rotating mirror 28 , which is on the disc 26 attached to the shaft 10 , and the flange 30 with the opening 32 which is attached to the spool 16 . If the mirror 28 and the flange 30 are travelling at the same speed (a condition which exists only when the tungsten filament has been broken), one of two conditions can take place, either the mirror 28 will be totally or partially in register with the opening 32 , in which case a flash of light will strike the photoelectric tube 38 with every revolution, or alternatively the mirror 28 will be obscured completely by the flange 30 and no flashes of light whatsoever will reach the photoelectric tube 38 . In any case, the photoelectric tube 38 will receive either constant flashes of light or no light at all.

Consider now the condition where the tungsten filament 18 has not been broken and the machine is operating normally. The mirror 28 and the flange 30 will not be travelling at the same speed, the flange will be travelling at a higher speed due to the spool's "paying-off" of the tungsten filament. Flashes of light will therefore reach the phototube 38 , but these flashes will not all be of the same intensity. A "beat" will occur at a frequency equal to the difference in speed of the mirror 28 and flange opening 32 , as for example, the mirror 28 one time around will be obscured by the flange 30 ; the next time the opening will just slightly uncover the mirror allowing a very weak flash to strike the phototube; each successive time around the opening will uncover more of the mirror, passing a slightly stronger flash, and so on until the entire mirror 28 is reflecting light to the photoelectric tube 38 . The opening 32 will then progressively advance so that with each revolution less and less of the mirror 28 will be visible to the photoelectric tube 38 , until again it is totally obscured by the flange 30 . This "beat" will, of course, be at a low frequency compared to the speed of the mirror itself, and it is this beat which causes the circuit to operate.

Going back to Fig. 3, consider first the case of the broken tungsten wire. If the mirror 28 is obscured by the flange 30 , no light at all strikes the photoelectric tube 38 , therefore the triode of tube V_1 continues to pass just a slight D. C. current through the primary of transformer T_2 and because a transformer will pass from primary to secondary only an alternating voltage, no voltage will appear at the secondary of this transformer. On the other hand, if the mirror 28 happens to be totally or partially in register with the opening 32 in the flange 30 and is travelling at the same speed, a flash of light will strike the phototube 38 with each revolution, but each flash will be of equal intensity, and the frequency of these flashes will be equal to the speed of the mirror and flange. These flashes will cause, as explained before, the triode section of tube V_1 to pass current through the primary of transformer T_2 , and since the light is in the form of flashes, the current through the primary of transformer T_2 will be in the form of pulses at a frequency equal to the speed of the mirror. Transformer T_2 will cause an A. C. voltage to appear across its secondary winding and across potentiometer P_2 . Considering for a moment that

the upper end of transformer T_2 secondary is momentarily positive, current will flow to the diode plate of tube V_3 to cathode of tube V_3 , through resistance R_5 and back to the other end of potentiometer P_2 . On the alternate half cycle when the upper end of transformer T_2 secondary is momentarily negative, due to the rectification of the diode section of tube V_3 no current will flow through resistance R_5 . A uni-directional current therefore flows through resistance R_5 , and due to the filtering action of condenser C_4 it is substantially D. C. of polarity as indicated and its magnitude depends upon the intensity of the light flashes. Since we are at the moment considering that the filament is broken and the flashes striking the photoelectric tube 38 are all of equal intensity, a D. C. voltage of constant magnitude appears across resistance R_5 . Since the grid of the triode section of tube V_3 is connected to the minus end of resistance R_5 , the triode section of tube V_3 may or may not be passing plate current through the primary of transformer T_3 depending upon the magnitude of the equal light flashes. In any case, the voltage on the grid of tube V_3 is D. C., therefore the plate current, if any, through the triode section of this tube will be D. C. As before, a transformer will develop a voltage across the secondary only if a varying current flows in its primary. In the case under discussion, therefore, no voltage appears across the secondary of transformer T_3 , and by the same reasoning applied to the first or diode section of V_4 , R_6 , and C_5 as was applied to the diode section of V_3 , R_5 , and C_4 , no voltage appears across R_6 . The grid of tube V_4 has no biasing voltage on it, therefore, and it draws plate current through and energizes the coil of relay 40 . Condenser C_6 serves to filter out the supply frequency pulsations across the coil of relay 40 .

We have seen up to this point that if the tungsten filament is broken, there are two situations that can exist: First, the mirror 28 may be completely obscured by the flange 30 so that no flashes at all reach the phototube. In this case no voltage appears across resistance R_5 , no voltage appears across resistance R_6 , and relay 40 is energized and its contacts will be held open. Secondly, the mirror 28 may be only partially or not at all obscured by the flange 30 so that light flashes of constant magnitude strike the phototube, a steady D. C. voltage does appear across R_5 , but no voltage can appear across R_6 , so that again relay 40 still remains energized with contacts open.

Consider now the case of the tungsten filament 18 not being broken and the device being operated normally, a beat of comparatively low frequency strikes the phototube 38 . This is due to the relatively small difference in speed of rotation of the mirror and the opening in the flange. The mirror 28 is uncovered by the opening 32 in the flange 30 only after a large number of rotations of the mirror and flange. A voltage will appear across R_5 but it will not be a constant. It will, rather, be a voltage whose magnitude varies with the beat frequency, since the time constant of R_5 and C_4 is insufficient to filter this low frequency. The bias on the triode section of tube V_3 will therefore vary with the beat frequency, current will flow in low frequency pulses through the primary of transformer T_3 , and low frequency voltage pulses will appear across the secondary of transformer T_3 and will be rectified by the first (or diode)

section of tube V_4 , and a voltage will appear across R_6 . The values of R_6 and C_5 are such as to give a time constant equal to or greater than this low frequency pulse, so a substantially pure D. C. appears across R_6 . Since the grid of the triode section of V_4 is connected to the minus end of R_6 , it will be biased to cut-off, the relay will no longer be energized and the contacts for the motor circuits will be closed. This is the case of the machine continuing to run.

What I claim is:

1. A control for filament wrapping machines in which a filament carrying spool during normal operation rotates with and at a different speed from guiding means therefor, an electronic circuit, a photoelectric tube therein, a mirror carried by said guiding means, a shield having an opening therein rotating with said spool whereby increasing and decreasing light flashes are imposed on said photoelectric tube, said photoelectric tube receiving said variable flashes of light from said mirror during normal operation, and said circuit operating a relay to stop said machine when said flashes cease or become constant.

2. A control for filament wrapping machines in which a filament carrying spool rotates with and at a different speed from guiding means therefor during operation, an electronic circuit having a photoelectric tube therein, a mirror carried by one of said rotating means, a shield having an opening therein carried by the other member, said photoelectric tube receiving periodic variable flashes of light as said mirror is variably uncovered by the opening in said shield at each

5
10

rotation during normal operation of the machine, and said circuit operating a relay to stop said machine when said flashes cease or become constant.

3. A control for filament wrapping machines comprising, filament guiding means, rotating means for said guiding means, means to feed a core wire axially of said guiding means, a spool rotatable with and relatively of said guiding means, a mirror mounted for rotation with said guiding means, a flange rotatable with said spool having an opening therein through which said mirror may be viewed during relative rotation of the shaft and spool, a light source, a photoelectric tube positioned to receive light from said source as reflected by said mirror, and an electronic circuit controlled by the flashes of light reflected by said mirror upon said photoelectric tube for controlling operation of said wrapping machine.
